UNITED STATES PATENT OFFICE

WILLIAM E. MATHEWS, OF BIRMINGHAM, ALABAMA, ASSIGNOR TO HARDIE-TYNES
MANUFACTURING COMPANY, A CORPORATION OF ALABAMA

COMPRESSOR UNLOADER

Application filed July 23, 1928. Serial No. 294,907.

My invention relates to operating means for valves, more particularly for compressor valves, and has for its object the provision of simple effective means for operating such valves either manually or in response to pressure.

A further object of my invention is to provide unloader means for a compressor valve including a pressure actuated piston and wherein valve means are embodied in the piston to obviate the necessity of packing the piston.

A still further object of my invention is to provide unloader means for a compressor valve including a pressure actuated piston having valve portions thereon, and wherein means are provided for cushioning the movements of the piston.

The usual mechanism for unloading air compressors, as is well known, comprises some means to hold the inlet valves of the compressor cylinders open during the compression stroke of the piston. In such mechanism it is usual to provide both pressure and manual operating means. Difficulties have been encountered in the design of such apparatus by reason of the heretofore common practice of providing packing for the pressure actuated member which, after being installed and in service for a period of time, begins to leak and render the operation of the apparatus erratic. Furthermore, it has heretofore been regarded necessary to provide packing around the stem of the manually operable means for the unloading mechanism to prevent leakage around the stem and this packing soon becomes worn and requires renewal.

These and other difficulties are overcome by means of my invention, wherein I have provided a pressure actuated unloader piston without packing and having valve portions formed on the piston and cooperating with its cylinder walls to prevent leakage thereby when the piston is at either limit of its travel. In order that the valve portions or their seats may not become damaged by pounding, I provide novel and effective means for cushioning the movements of the piston. Manually operable means is also provided to

coact with the piston, when desired to hold the valve open and is so constructed as to require no packing to prevent leakage thereby. Furthermore, the manually operable means embodies novel details of construction which render it operable over long periods of time without attention or repairs.

Apparatus embodying features of my invention is illustrated in the accompanying drawing, forming a part of this application, wherein

Fig. 1 is a vertical section through the apparatus; and

Fig. 2 is a detail sectional view of a part of the manually operable mechanism.

Referring to the drawing for a better understanding of my invention, I show a fragment of a compressor cylinder 10 having an inlet passage 11 along the wall thereof and having a wall provided with a shouldered recess 12 for the reception of an inlet valve 13, said valve being of the ring plate type and embodying a plurality of ring plates 14 held against their seats by springs 16, only one of which is shown.

In the outer wall of the inlet passage 11 is provided an opening 17 over which is secured a valve bonnet 18. The valve bonnet 18 has a threaded opening 19 therein for receiving a cylindrical casing 21. The casing 21 is hollow and has positioned therein an unloader piston 30, said piston having a limited range of reciprocable movement within the casing. The lower end of the casing 21 is provided with a flange 22 and bearing against the flange 22 is an outwardly threaded sleeve 23 fitting loosely over the casing 21 and screwing into the opening 19 to hold the casing in place. The sleeve 23 is locked in position by means of a lock nut 24 screwed on over the sleeve and bearing against the valve bonnet.

The valve 13 is held in place by means of a keeper 26 terminating in a ring 27 which bears against the valve 13. The upper end of the keeper 26 is in the form of a ring with a cylindrical bore 28 in alignment with the bore of the casing 21 and having a bushing 29 interposed therein between the lower end of the casing 21 and the keeper 26. The bore 28 is of such size that the flange 22 of the casing 21

55

fits snugly therein and thus serves to center the keeper with respect to the casing.

Disposed within the lower end of the casing 21 is a piston 30. The piston 30 is provided, at its upper end, with a beveled valve portion 31 and the casing 21 is bored to form a seat 32 against which the valve 31 rests when the piston is in its upper position. The piston 30 is also provided, at its lower end, with a valve portion 33 which fits against the bushing 29 when the piston is in its lower position. Thus, in either position of the piston, leakage thereby is prevented and no packing is required therefor.

15 The lower end of the piston is provided with an inwardly extending stem portion 36 and the bore of the bushing 29 is made of a size to provide a smooth sliding fit for the stem portion 36. The lower end of the stem 20 36 is threaded as at 37 and an operating fork 38 is screwed on to the lower end thereof. The operating fork 38 has its upper portion turned to form a piston portion 39 which fits snugly in the lower end of the bore of the 25 keeper 26. The operating fork 38 is provided at its lower end with fingers 41 which are adapted to bear against the ring plates 14 to hold the valve open. It will be seen, upon movements of the piston 30, that there is a 30 small air pocket 42 between the piston portion 39 and the bushing 29 forming a dash pot and cushioning the movements of the piston, thus preventing damage to the valve portions of the piston and their seats.

35 In order that air entrapped beneath the piston 30 shall not interfere with its action in opening the valve 13, I provide relief ports 43 through the wall of the keeper 26 and extending through the bushing 29, the bushing 40 29 being grooved at 44 so that there is always communication through the keeper and through the bushing with the side of the piston stem 36. The piston stem 36 is turned to provide a groove 45 around it and which extends upwardly to the lower valve portion 33.

45 In order that the fingers 41 of the operating fork 38 shall not bear against the ring plates 14 except in opening the valve, I provide a spring 46 between the lower end of the 50 piston stem 36 and the valve 13, the valve 13 being provided with a recess 47 for positioning the lower end of the spring. Air for operation of the piston 30 is admitted at the upper end of the casing through a conduit 48.

55 The piston 30 is made hollow at its upper end, the hollow thereof being provided with a shoulder 51. Fitting loosely within the hollow of the piston is a rod 52 which extends upwardly and is provided, near its upper end, with an elongated hole 53. Extending through the hole 53 and into the wall of the casing is a pin 54 which holds the rod against 60 rotary movement while the elongated hole permits the rod a limited longitudinal movement. Surrounding the rod 52 near its upper

end is a collar 56 which acts as an abutment for a spring 57 disposed between the collar 56 and the shoulder 51 in the hollow of the piston. The collar 56 is held in fixed position by the pin 54 as may be more clearly seen in Fig. 2. It is made sufficiently thin to provide ample clearance around it for passage of pressure to operate the piston 30.

70 The spring 57 is employed where the unloader is used with valves operating with pressure higher than atmospheric pressure, such, for example, as the high pressure inlet valves of a multi-stage compressor. Where so used, the spring 57 is made of sufficient strength to nearly balance the inlet pressure acting against the piston portion 39 of the operating fork 38 and against the lower end of the piston 30.

75 Near the upper end of the rod 52, a pin 61 extends transversely therethrough and acts as a cam to cooperate with a cam surface 62 formed on the lower end of a manually operable stem 63 which extends downwardly through the upper end of the casing 21. The lower end of the stem 63 is hollowed out to receive the upper turned end 64 of the rod 52 which thereby maintains the rod and the stem in alignment. Disposed between the collar 56 and the pin 61 is a spring 65 which bears the weight of the manually operable mechanism and holds the rod 52 normally away from the piston 30 and holds the stem 63 in its upper position.

80 The stem 63, where it projects through the casing 21, is provided with a beveled valve portion 66 which seats against a seat 67 formed in the outer end of the casing, thereby obviating the necessity of packing the stem 63; the pressure within the casing holding the valve on the seat. At the upper end of the 85 stem 63 is mounted a balanced handle 70 having a sector 68 cut out on its underside which cooperates with a pin 69 provided in the casing 21 to limit the range of movement of the handle 67.

90 From the foregoing description the operation of my invention will be readily understood. When pressure is admitted to the casing 21 through the conduit 48 it forces the piston 30 downwardly so that the valve portion 33 seats against the bushing 29, preventing leakage of air past the piston and forcing the operating fork 38 downwardly with the fingers 41 to push the ring plates 14 off their seats. At the same time, air beneath the piston 30 passes outwardly through the ports 43 into the inlet passage 11. When pressure is released from above the piston 30, the spring 46 pushes the unloading fork 38 and piston 30 upwardly until the valve portion 31 is against the seat 32. If the pressure in the inlet passage 11 be above atmospheric, the valve portion 31 seals the piston against leakage. Thus, with this arrangement, the piston 30 may be a relatively loose

fit, without danger of leakage, and be quickly responsive to pressure operation.

Whenever it is desired to operate the device manually, the handle 70 is turned to bring the cam surfaces 61 and 62 carried by the rod 52 and stem 63, respectively, into operative relation to force the rod downwardly against the piston 30, causing the piston to move downwardly and again open the valve. In order to permit the valve to again close, the handle 70 is turned in the opposite direction to move the cam 62 away from the pin 61 whereupon the spring 46 again raises the piston 30 and carries the operating fork 38 upwardly away from the ring plates. At the same time the spring 65 holds the valve portion 66 of the stem 63 against its seat 67.

From the foregoing, it will be apparent that I have devised an apparatus for manual and pressure actuated operation of a compressor unloader which is simple of design and reliable in operation and which may remain in service for an indefinite period of time without necessity of repairing.

While I have shown my invention in but one form, it will be obvious to those skilled in the art that it is not so limited but is susceptible of various changes and modifications without departing from the spirit thereof and I desire therefore that only such limitations shall be placed thereupon as are imposed by the prior art or as are specifically set forth in the appended claims.

What I claim is:

1. A device for opening and closing the unloading valve of a compressor, comprising a casing, a pressure operated piston mounted for reciprocable movement within the casing and having valve portions on the opposed sides thereof, means for supplying pressure to operate the piston, means forming seats for the valve portions and adapted to prevent leakage of pressure by the pressure operated piston when seated, and an operating fork connected directly to the piston and extending to the valve for transmitting movements of the piston to the valve.

2. A device for opening and closing valves in the unloading of compressors, comprising a casing, a pressure operated piston mounted for reciprocable movement within the casing and having valve portions on the opposed sides thereof, means for supplying pressure to operate the piston, means forming seats for the valve portions and adapted to prevent leakage of pressure by the piston when seated, a stem on the piston projecting inwardly from the casing, an operating fork secured to the stem to transmit movement of the piston to the valve, a piston member carried by the fork, a cylinder for the piston member to cushion the movements of the piston, and means provided to release medium entrapped beneath the piston upon movement thereof in a direction to open the valve.

3. In a device for operating compressor valves, a casing embodying a cylinder, an operating piston in the cylinder, valve portions formed on the opposed faces of the operating piston, means providing seats for the valve portions of the operating piston to prevent leakage thereby when seated, an inwardly projecting stem on the operating piston, an unloading fork connected to the stem, compressor valve members operated by the fork, a dash pot piston on the fork, a cylinder for the dash pot piston to cushion movements of the operating piston upon actuation thereof, and means to admit air to the casing on the outer side of the operating piston for actuation of the latter.

4. In an unloader apparatus for a compressor valve, a valve housing having a recess for positioning the compressor valve, a valve bonnet arranged outwardly of the recess and having a threaded opening coaxially therewith, a hollow casing having a cylindrical bore therein extending through the opening and having a flange on its inner end, a threaded sleeve surrounding the casing and screwed into the opening to bear against the flange, a valve keeper interposed between the casing and the valve and forced against the compressor valve by the casing, said keeper having a cylindrical bore in alignment with the bore in the casing and receiving the flange of the casing, a bushing having a reduced bore positioned in the bore of the keeper, a piston having valve means on its opposed faces disposed within the casing and having an extension projecting into the bore of the bushing, an unloader fork secured to the extension and turned to fit the bore in the keeper and to cushion against the bushing, means forming seats for the valve portions of the piston, and means to admit air for operation of the piston on the outer side thereof.

5. An operating means for opening and closing compressor valves comprising a cylindrical casing, a pressure actuated piston disposed within the casing, means for transmitting movements of the piston to the valve, a rod having one end adapted to bear against the piston, a cam within the casing on the other end of the rod, a manually operable stem projecting outwardly of the casing, in alignment with the rod, and a cam provided on the inner end of the stem for cooperating with the cam on the rod to actuate the latter.

6. An operating means for opening and closing compressor valves comprising a cylindrical casing, a pressure actuated piston disposed within the casing, means for transmitting movements of the piston to the valve, a rod having one end positioned to bear against the piston, a cam within the casing on the other end of the rod, a manually operable stem projecting outwardly of the casing in alignment with the rod, a cam provided on

the inner end of the stem for cooperating with the cam on the rod to actuate the latter, a shoulder on the stem forming a valve where the stem projects through the casing, and a seat formed on the inner side of the casing 70 cooperating with the shoulder to prevent leakage thereby outwardly of the casing.

7. An operating means for opening and closing compressor valves comprising a cylindrical casing, a pressure actuated piston disposed within the casing, means for transmitting movements of the piston to the valve, a rod having one end adapted to bear against the piston, a cam within the casing on the other end of the rod, a manually operable stem projecting outwardly of the casing, a cam provided on the inner end of the stem for cooperating with the cam on the rod to actuate the latter, means for maintaining the stem 80 and the rod in alignment, means for holding the rod against rotary movement, a shoulder on the stem forming a valve where the stem projects through the casing, and a seat formed on the inner side of the casing 85 cooperating with the shoulder to prevent leakage thereby outwardly of the casing.

8. An operating means for opening and closing compressor valves comprising a cylindrical casing, a hollow pressure actuated piston disposed within the casing, means for transmitting movements of the piston to the valve, a rod having one end fitting in the hollow of the piston, a cam within the casing on the other end of the rod, a manually operable stem projecting outwardly of the casing, a cam provided on the inner end of the stem for cooperating with the cam surface of the rod to actuate the latter in a direction to open the valve, spring means for closing the valve 95 when the stem is turned in a direction to separate the cams, means for maintaining the stem and the rod in alignment, means for holding the rod against rotary movement, a shoulder on the stem forming a valve where the stem projects through the casing, and a seat formed 100 on the inner side of the casing cooperating with the shoulder to prevent leakage outwardly of the casing.

9. An operating means for opening and closing compressor valves comprising a cylindrical casing, a hollow pressure actuated piston disposed within the casing, means for transmitting movements of the piston, a rod having one end fitting in the hollow of the piston, a cam within the casing on the other end of the rod, a manually operable stem projecting outwardly of the casing, a cam provided on the inner end of the stem for cooperating with the cam surface of the rod to actuate the latter in a direction to open the valve, spring means for closing the valve when the stem is turned in a direction to separate the cams, means for maintaining the stem and the rod in alignment, means for holding the rod 115 against rotary movement, a shoulder on the 120

stem forming a valve where the stem projects through the casing, a seat formed on the inner side of the casing cooperating with the shoulder to prevent leakage outwardly of the casing, and spring means for normally holding 70 the rod away from the piston and for holding the shoulder on the stem against its seat.

In testimony whereof I affix my signature.

WILLIAM E. MATHEWS.
